UNITED STATES PATENT OFFICE.

HARRY O. DORSEY, OF ATLANTA, GEORGIA.

FURNACE-GRAVE.

1,274,147.

Specification of Letters Patent. Patented July 30, 1918.

Application filed November 14, 1917. Serial No. 201,965.

To all whom it may concern:

Be it known that I, HARRY O. DORSEY, a citizen of the United States of America, and a resident of Atlanta, county of Fulton, and 5 State of Georgia, have invented certain new and useful Improvements in Furnace-Grates, of which the following is a full and clear specification.

This invention relates to that type of 10 forced draft furnace grates in which the fuel-supporting surface is constructed of a series of closely spaced hollow sections in the top wall of each of which is formed a series of circular nozzles formed by circular holes 15 in the top wall in each of which is fitted a circular beveled cover or disk, the beveled edge of the disk being held away from the correspondingly beveled edge of the opening to form a circular air-supplying slit; and 20 one of the objects of the present invention is to improve and simplify the manner of fastening the nozzle plates in position in the grate bar, whereby they may be more readily removed from time to time for cleaning 25 or repairing, as more fully hereinafter set forth.

Another object is to provide simple means for latching the nozzle plates in place, to thereby provide a still further security 30 against dislodgment of these plates during the act of cleaning off the grate surface; and a still further object is to provide simple means whereby the ashes which sift down through the air openings onto the bottom 35 of the hollow sections may be readily removed therefrom and deposited underneath the grate, as more fully hereinafter set forth.

In the drawing—

40 Figure 1 is a side elevation, partly broken away, of a grate section constructed in accordance with my invention; and

Fig. 2 is a vertical sectional view on the line 2—2 of Fig. 1.

45 Referring to the drawing annexed by reference characters, *a* designates the hollow grate bar or section which is approximately rectangular in cross-section and is provided with a flat top surface. At intervals along

50 the bar, circular openings are formed in the top wall of the bar, the wall of each opening

being beveled downwardly. In each of these openings is fitted a nozzle disk *b* beveled at its edge to correspond with the bevel of the opening, the beveled edge of the disk 55 being provided with several vertical ribs *c* to space the disk a short distance away from the beveled wall of the opening, to thereby provide the usual annular air passage.

60 Projecting inwardly from each side-wall of the channel bar, adjacent to each opening, is a lug *d*, and formed on each disk *b* are two pairs of depending lugs *e*, so positioned on the disk as to embrace or straddle the 65 lugs *d* when the disk is in place. These depending lugs or fingers *e* loosely embrace lugs *d*, so that the disk may be quickly and readily detached from the bar by simply lifting it out of the opening. The interlocking lugs tend to prevent the disk from being tilted and dislodged while in use. The former way of securing these disks was to lock them in place by a bar and bolts, so that when the disks had to be repaired or 70 renewed it was necessary to draw the fire and allow the furnace to cool down and then remove the nuts and bolts and bar, thereby entailing a loss of time which frequently amounted to two days. With my 75 construction, it will be simply necessary to part the fire-bed along the grate bar that is to be repaired sufficiently to expose the disks that are to be renewed, and then with a suitable tool pry up the broken or defective disks and replace them by new ones, the new disks being simply dropped into place with their fingers *e* in engagement 80 with the inwardly-extending lugs *d*. It will be observed, therefore, that my device makes 85 it possible to avoid a great deal of delay in making repairs to the nozzles.

89 It will be observed that by employing a series of lugs along the inner faces of the walls of the bar as a means for locking the nozzle plates, there will be no danger of disturbing the relative location of the lugs with reference to the openings by the warping or twisting of the bar under the heat of the furnace.

100 To still further lock the nozzle plates against accidental removal by the cleaning,

scraping or stirring tool, I pivotally depend from each disk a pair of hooks *g* which normally swing under the lugs *d* and thus latch the air disk in place. By swinging 5 these hooks inwardly toward each other, the disk may be readily withdrawn and replaced by another. The lower ends of the hooks are beveled, so as to automatically latch under the lugs when the disk is dropped into 10 place.

The bottom wall *h* of the hollow section inclines downwardly and forwardly from the air-inlet *i* to the forward end of the section, and this forward end of the section 15 is provided with an opening which is normally closed by a door *j* pivoted at its lower end to the bottom wall and adapted to swing downwardly, as shown in dotted lines. The door is operated by means of a bell- 20 crank *k*, one arm of which is pivoted at *l* to the door and the other arm of which is pivotally connected to an operating rod *m*; and to hold the door normally closed I append to the bell-crank a weight *n*. By opening the door *j* from time to time, the blast of 25 air usually supplied through the inlet *i* will, instead of passing up through the air openings in the surface of the grate, pass out through the uncovered opening in the outer 30 end of the bar and thus blow out the ashes dust that accumulates within the hollow section, thereby providing a simple means for preventing the dust accumulating in the sections sufficiently to cause injury to the 35 top wall of the air nozzles by burning. The door at the front of the section also permits ready inspection from time to time of the interior of the section, and it will be observed, of course, that if the blast of air 40 does not entirely clean out the dust, the remaining dust may be readily raked out.

It will be observed that the ash-exit is in the end wall of the section, that is, at the lower corner, at the junction of the 45 bottom wall and the end wall, so that if ashes accumulate on the bottom of the section they may be readily raked out; and it will be seen further that this arrangement of the exit opening permits ready inspection 50 of the interior of the section throughout its full length.

It will be observed that lugs *d* together with the depending pairs of fingers *e* prevent the nozzle plate being rotated by the cleaning 55 tools, thereby preventing accidental dislodgment of the nozzle plates, and it will be observed also that the lugs *d* are located on the side walls of the section at a distance below the nozzle opening, so as to 60 thereby prevent any accumulation of ashes on the top sides of the lugs *d* from interfering with the placing of the nozzle plates in position. This location of the lugs *d* also facilitates the use of normally-operating

hooks *g* since it permits the hooks to be 65 made long enough to have the necessary swinging action as well as large enough to operate efficiently over a long period of time.

The nature and scope of the invention 70 having thus been indicated and its preferred embodiment having been specifically described, what is claimed as new is:

1. A channel grate-bar provided with 75 holes at intervals in its top surface and also a pair of inwardly-extending lugs at a distance below the top surface of the bar, one pair of oppositely-extending lugs being arranged under each opening, each nozzle plate being provided with two pairs of depending fingers, each pair being adapted to embrace one of said lugs and thus prevent the nozzle plates from rotating.

2. A channel grate-bar provided with 80 holes at intervals in its top surface and also a pair of inwardly-extending lugs at a distance below the top surface of the bar, one pair of oppositely-extending lugs being arranged under each opening, each nozzle plate being provided with a pair of pivotal 90 depending hooks normally engaging under said lugs, and also with depending fingers engaging said lugs to guide the hooks into proper engagement with said lugs, for the purpose set forth.

3. A hollow grate bar or section provided 95 with air-escape openings in its top surface, an inlet at one end to admit air under pressure, and an ash-exit at its other end, this exit being formed at the junction of the bottom-wall and the adjacent end-wall of the section to thereby form an unobstructed opening at this end of the bar, the bottom-wall being inclined from said air-inlet to said ash-exit to thereby permit the air 100 supply to assist in discharging the ashes, a pivoted closure-plate for the ash-exit, devices for normally closing this plate against air-pressure in the section, and means for opening said closure-plate.

4. A hollow grate-bar or section provided 105 with air-escape openings in its top surface, an air-inlet at one end and an ash-exit at its other end, this exit being formed at the juncture of the bottom-wall and the adjacent end-wall of the bar to thereby form an unobstructed opening at this end of the bar, said bottom-wall being inclined from 110 said air-inlet to said ash-exit to thereby permit the air-pressure to be utilized in assisting in discharging the ashes at said ash-exit, a closure plate for this opening, and means for operating this closure-plate.

5. A hollow grate bar or section provided 115 with air-escape openings in its top surface, an air-inlet at one end, an ash-exit at its other end, this exit being formed at the juncture of the bottom-wall and the ad-

jacent end-wall of the bar, to thereby form an unobstructed opening at this end of the bar, a pivoted closure-plate for this opening, and means for operating this closure-plate, said means consisting of an angle-lever pivotally mounted on the bar and having one end in pivotal engagement with the closure-plate, an operating rod connected to the other arm of the angle-lever, and a weight connected to the angle-lever tending 10 to normally close the closure-plate.

In testimony whereof I hereunto affix my signature.

HARRY O. DORSEY.
